UNITED STATES PATENT OFFICE

LEWIE L. BELNAP, OF OAKLAND, CALIFORNIA

PORTABLE SAW STANDARD

Application filed January 3, 1927. Serial No. 158,524.

The present invention relates to improvements in wood working tools and has particular reference to a universal wood working tool such as described in my co-pending application, Serial No. 67,719, filed November 9, 1925. In the present invention, it is proposed to provide the improvement in connection with the standard or supporting means for the arm of the wood-working tool from which the saw is suspended, and it is particularly proposed in this connection to somewhat simplify the operation of the device. In its general features, my wood working tool comprises a mast supported in a mast housing which stands back from the front edge of a bench. The mast on which the tool arm is supported is mounted with freedom of vertical, as well as angular adjustment, and the means by which the adjustments are effected are brought to the front edge of the bench so that the operator need not walk around the tool in order to make adjustments. In the present invention, it is proposed to somewhat simplify the controls and to centralize the same by reducing the number thereof. It is further proposed to place the vital parts of the working mechanism for effecting control on the inside of the mast housing so that these parts are safe from injury due to improper handling or other causes while, at the same time, lubrication may be applied in a more perfect manner. It is further proposed to provide certain improvements in the design which render the tools as a whole easier to manipulate and safe to operate.

Further objects and advantages of the present invention will appear as the specification proceeds.

The preferred form of my invention is illustrated in the accompanying drawing in which—

Figure 1 shows a side view of the assembled supporting means for a wood working tool, the arm from which the tool itself is supported being omitted.

Figure 2 a vertical section thru the standard forming a part of the supporting means,

Figure 3 a vertical section along line 3—3 of Figure 1, and

Figure 4 a horizontal section taken along

line 4—4 of Figure 2, slightly reduced in scale.

While I have shown only the preferred form of the invention, I wish to have it understood that various changes or modifications may be made within the scope of the claims hereto attached without departing from the spirit of the invention.

Referring to the drawing in detail, it will be seen that the mast housing 1 is supported relative to the bench 2 at a distance from the front edge 3 thereof by means of a flange 4 resting on the bench and secured thereto by bolts 6. It will be noted that a considerable section of the housing extends below the bench.

Referring now particularly to Figure 2, it will be noted that in the housing, substantially at the elevation of the flange 4, there is provided a flange 7 into which is threaded a nut 8 accommodating a bearing 9 which bearing is held in place by means of a second nut 11 threaded into the lower end of the first nut. From the bearing is suspended, by means of a collar 12, the long sleeve 13 extending substantially throughout the length of the housing and threaded in the upper portion thereof as shown at 14. This sleeve carries a worm gear 16 at the lower end thereof which gear meshes with a worm 17 on the horizontal shaft 18 extending forwardly thru the wall of the housing to the front edge of the bench and provided at its front end with an operating wheel 19. The worm gear 16 forms part of a bushing 21 fixed relative to the sleeve by means of screws 22 and spaced from the bearing 9 by a spacing member 23.

The mast 24 is supported in the upper section 26 of the housing in such a manner that the mast may be raised or lowered by a turning movement of the sleeve 13. The latter threadably engages with a nut 27 threaded into a plate 28 on which latter rests an internal flange 29 of the mast, the said flange being secured to the plate 28 by means of bolts 31. It will be noted that this arrangement causes the mast to move axially when the sleeve 13 is revolved, provided the mast itself is held against revolving motion.

Inside of the sleeve 13 there is provided a shaft 32 which extends above and below the sleeve and is provided below the sleeve with a clutch element 33 slidable thereon, but held 5 against revolving motion by keys 34 running in key ways 36. This clutch element is provided with jaws 37 adapted to mesh with corresponding jaws 38 on the worm gear 16 when the clutch element is lifted by means of 10 a yoke 39 pivoted on the shaft 41. The latter shaft extends thru the wall of the housing and has a bell crank lever 42 fixed thereto, one arm 43 of the lever being acted on by a spring 44 which normally holds the clutch element 15 away from the worm gear. The longer arm 46 of the lever is connected by means of a vertical rod 47 to an arm 48 of a second lever 49 pivoted to the housing as shown at 50. A second arm 51 of this lever is connected to a 20 horizontal rod 52 extending forwardly thruout the width of the bench and terminating in a shaft 53 slidably mounted in a face plate 54 secured to the front edge of the bench by means of screws 56. When the shaft 53 is 25 pulled forward by means of a handle 57, a latch 58 drops by its own weight into an annular groove 59 provided in the shaft for locking the latter against rearward motion. It will be noted that when the shaft 53 is 30 pulled forward, the rod 47 is pulled upward and actuates the lever 42 to push the clutch element 43 up against and into engagement with the worm gear 16, whereby the shaft 32 is 35 connected to the sleeve 13 to form a unit therewith. The upper end of the shaft 32 is provided with a cross head 61 which latter slides on two vertical rods 62 supported between the plate 28 previously mentioned and a second plate 63 provided in the mast above the 40 plate 28 and in spaced relation thereto. It will be noted that while the rods 62 do not prevent the mast from moving axially, they do prevent rotary motion relative to the shaft 32.

45 It will be understood that when the mast is held against rotary motion and the sleeve is revolved, the mast moves axially due to the action of the threads 13, but when the clutch 33 is engaged with the worm gear whereby the shaft 32 and the sleeve 13 are united, then revolving motion of the sleeve will cause the mast to revolve due to the fact that the rods 62 are actuated by the cross head 61. The mast may be held against rotation or made 50 free to rotate at the option of the operator by the arrangement shown in detail in Figure 3.

55 A trigger 66 is pivoted as shown at 67 in a plate 68 secured in an opening 69 in the wall of the mast housing with freedom of lateral adjustability by means of guide pieces 73 and 74 secured to the mast housing above and below the opening 69 by means of screws 76. The guide pieces have flanges 71 and 72 extending therefrom adapted to ride in register-

ing grooves in the top and bottom faces of the plate. The flanges are arc-shaped and their arcs are drawn relative to the axis of the mast housing so that when the plate 68 is adjusted laterally, the trigger 66 always 70 points toward the axis of the housing, and lies in a radial plane. Adjustment of the plate 68 may be effected by means of screws 77 threaded into lugs 78 projecting from the face of the housing and bearing on opposite sides of the plate, the screws being locked in position by lock nuts 79 bearing on the lugs. When the trigger 66 is in the horizontal position indicated in Figure 3, its front edge engages with one of a plurality of vertical 75 grooves 81 provided in the mast as shown particularly well in Figure 4 and thereby locks the mast against rotary movement. The trigger may be operated by means of the vertical rod 82 engaging the free end of the 80 trigger as shown at 83 and connected to an arm 84 of the lever 49 so that when the latter is actuated by means of a forward pull on the rod 52, the free end of the trigger 66 is pulled downward, and the front end of the trigger 90 disengages from the grooves 81 of the mast, thereby allowing the latter to turn. It will be noted that the rod 82 is preferably made of two sections 82' and 82'' loosely jointed as at 86. A spring 87 resting in a cup 88 disposed on a lug 89 extending from the guide piece 74 tends to force the trigger into active position.

95 Adjustment of the mast for accurate results may be secured in the following manner: A guide piece 91 is secured on the bench 2 in a position approximately parallel to the front edge of the bench and the mast arm is then swung into a position causing a piece of wood placed against the guide 91 to be cut 100 at a certain angle, say a right angle, when the saw blade is moved in the direction of the arm extending from the mast. If the cut 105 actually made proves to be a true right angle, the adjustment of the mast relative to the 110 mast housing is correct; but if the angle slightly varies from a 90° angle, proper adjustment may be obtained by shifting the plate 68 by means of the screws 77 until proper results are obtained. It will be understood, of course, that once the correct setting 115 has been obtained, no resetting will be necessary until thru shipping, moving, or continued use for a long period of time, warping, etc., conditions have changed so as to 120 throw the guide 91 out of adjustment relative to the mast.

125 It will be noted from the position of the grooves shown in Figure 4, that they allow the mast to be held by the trigger 66 in a number of clearly defined positions, spaced 45° apart. If it is desired to temporarily lock the mast in any other position, the operator may use for this purpose the set screw 91' threaded into a bottom cap 92 of the mast 130

housing as at 93 and entering an annular groove 94 in the shaft 32 to bear against the bottom of the groove and to thereby hold the shaft against rotation. The set screw 91' is operated by means of a long rod 96 and a hand wheel 97 disposed at the front end thereof at the front edge of the bench. It will be noted that a second set screw 97' is threaded into the cap and enters the groove 94. This set screw is not intended to contact with the bottom of the groove, but only holds the shaft against axial movement.

The mast housing may be clamped upon the mast by operation of the handle 97 thru the horizontal rod 98, the vertical rod 99, and oppositely threaded screws 101 drawing confronting edges of the slotted housing together. This particular feature has been described in my co-pending application and does not form a part of the present invention.

The operation of my invention will be understood from the foregoing description. It will be noted that all adjusting is done by means of the single hand wheel 19. If it is desired to raise or lower the mast, it is only necessary to turn this hand wheel which, thru the worm gear 16, revolves the sleeve 13 and causes the mast to move axially thru the threaded end 14 of the sleeve engaging the nut 27. If it is desired to change the angularity of the mast, the rod 52 is pulled forward by means of the handle 57 and locked in its forward position by means of the latch 58. This causes the rod 47 to be pulled upward and the rods 82 to be pulled downward with the result that the clutch 33 ties the shaft 32 and the sleeve 13 into one unit while the trigger 66 is withdrawn from the slots 81 in the mast it was engaged with. If now the hand wheel 19 is turned, the mast will revolve and may now be turned to any of the other 45° positions indicated in Figure 4 when it will be held in position by the trigger 66 after the same has been released from the latch 58 or in any intermediate position by tightening of the set screw 91 thru the hand wheel 97.

Proper adjustment of the position of the trigger 66 so as to insure rectangular position of the mast arm relative to the guide board 91' in one of the positions using grooves 81 is secured by manipulation of the screws 77 in the manner previously described.

I claim:

55. 1. A standard for a universal tool of the character described, comprising a mast housing, a sleeve revolvably suspended in said housing, means for revolving the sleeve; a mast threadedly supported on the sleeve; a shaft in said sleeve and connected beyond the end of the sleeve to the mast so as to lock the mast against rotary motion and to cause the same to move endwise when the sleeve is rotated; and means slidable on the shaft for connecting the shaft to the sleeve, thereby

causing the rotation of the mast with the sleeve.

2. A standard for a universal tool of the character described, comprising a mast housing; a sleeve rotatably suspended in said housing; a mast threadedly supported on said sleeve; a concentric shaft inside of the sleeve, being connected with the mast beyond the end of the sleeve so as to lock the mast against rotary motion and to cause the same to move endwise when the sleeve is rotated; said sleeve being rotatable on said shaft, means for rotating said sleeve; means slidable on the shaft for connecting said shaft to an end of the sleeve, thereby causing the rotation of the mast with the sleeve; and means for sliding the said connecting means on the shaft into and out of engagement with the end of the sleeve.

3. A standard for a universal tool of the character described, comprising a mast housing, a sleeve revolvably suspended in said housing; a mast threadedly supported relative to said sleeve; a shaft extending thru the sleeve; means for fixing the shaft relative to the mast for common rotary motion; means for revolving the sleeve for imparting endwise motion to the mast; and means for connecting the shaft to the sleeve, whereby the endwise motion of the mast is changed to revolving motion; the means for fixing the shaft relative to the mast comprising spaced plates within the mast, vertical elements connecting the same, and a cross head on the shaft interlocking with the vertical elements.

4. A standard for a universal tool of the character described, comprising a mast housing, a sleeve revolvably suspended in said housing, a plate threaded relative to the sleeve, a mast supported on said plate, a second plate in the mast spaced from the former plate, upright members supported between the plates, a shaft revolvable within the sleeve and a cross head on the shaft interlocking with the upright members.

5. A standard for a universal tool of the character described, comprising a mast housing, a sleeve revolvably suspended in said housing, a plate threadedly supported relative to the sleeve, a mast formed with an internal flange adapted to rest on the plate, a second plate in the mast above the former plate and spaced therefrom, upright members supported between the plates, a shaft revolvable within the sleeve and a cross head on the shaft interlocking with the upright members, the cross head and the flange being formed so as to allow the cross head to be withdrawn through the flange.

6. A standard for a universal tool of the character described, comprising a mast housing, a sleeve revolvable therein, a mast threadedly supported on said sleeve, a shaft inside the sleeve and connected beyond an end of the sleeve to the mast so as to prevent the

rotary motion of the mast with the sleeve; a worm drive for revolving the sleeve so as to cause endwise movement of the mast thereon; and means slidable on the shaft for connecting the shaft to an end of the sleeve, thereby causing the rotation of the shaft, the mast, and the sleeve as a unit.

7. A standard for a universal tool of the character described, comprising a mast housing, two concentric shafts supported therein, a worm gear on the outer shaft, a worm for revolving the same, a clutch slidable on the inner shaft adapted for engagement with the outer shaft, a mast threaded on the outer shaft, said inner shaft having axially slid-
10 able, but non-rotatable engagement with said mast, means for normally locking the mast against revolving motion and means for engaging the clutch having means associated therewith for simultaneously releasing the locking means.

8. A standard for a universal tool of the character described, comprising a mast housing, two concentric shafts revolvable therein;
20 a mast threadedly supported relative to the outer concentric shaft; means for imparting rotary motion to the outer concentric shaft; the inner shaft being connected beyond the end of the outer shaft to the mast so as to prevent the rotary motion of the mast with the outer shaft, thereby causing endwise movement of the mast when the outer shaft is rotated; and means slidable on the inner shaft for connecting the inner shaft to the outer shaft for transmitting rotary movement from the outer shaft to the mast.

9. A standard for a universal tool of the character described, comprising a mast housing, two concentric shafts revolvable therein,
20 a mast threadedly supported relative to one of the shafts and fixed against rotary motion relative to the other shaft, means for imparting rotary motion to the former shaft and means for connecting the second shaft to the first shaft for revolving the mast, the latter means comprising a clutch element, slidable on one of the shafts, a yoke for shifting the same, a bell crank lever on the outside of the housing operating the yoke, a second bell
45 crank lever above the first lever, a rod connecting one arm of one of the said levers with one arm of the other lever, a horizontal rod extending forwardly from the other arm of the second lever so as to allow the yoke to be operated by a forward pull on the latter rod, and means for locking the said rod in a forward position.

In testimony whereof I affix my signature.
LEWIE L. BELNAP.
